[57] **CLAIM**

The ornamental design for a fluid nozzle for high-velocity fluid streams, as shown.

DESCRIPTION

FIG. 1 is a perspective view of a fluid nozzle for high-velocity fluid streams showing my new design;

FIG. 2 is a rear-elevational view thereof.

FIG. 3 is an elevational view taken from the side opposite that shown in FIG. 1;

FIG. 4 is a bottom plan view thereof; and

FIG. 5 is a top plan view thereof.
